ADJUSTABLE SHAFT MOUNTING

Sydney E. Pettigrew, Portland, Oreg., assignor of
one-half to Don B. Card, Portland, Oreg.

Application April 13, 1951, Serial No. 220,837

1 Claim. (Cl. 308—62)

1

This invention relates generally to tighteners for endless chains and belts and particularly to a means whereby the axes of the pulleys or sprocket wheels may be held along a given line.

The main object of this invention is to provide a simple and effective means for tightening a belt, chain or conveyor without changing the position of the runs of the chain or belt during or after the tightening operation.

The second object is to make it possible to adjust the elevation of the end of a belt or chain and to hold it there during subsequent tightening.

I accomplish these and other objects in the manner set forth in the following specification as illustrated in the accompanying drawing, in which:

Fig. 1 is a fragmentary section through the device taken along the line 1—1 in Fig. 2.

Fig. 2 is a section taken along the line 2—2 in Fig. 1.

Fig. 3 is a diagrammatic view showing the relative positions of the related parts.

Like numbers of reference refer to the same or similar parts throughout the several views.

Referring in detail to the drawing there is shown a representative form of side frame 10 which may, for example, be part of a conveyor. To the side frame 10 is secured a concentric ring 11 which is mounted concentrically with relation to the large hole 12 formed in the side frame 10, to which it is secured by means of the rivets 13.

Within the ring 11 and against the frame 10 is disposed the revolvable disk 14 having holes 15 formed around its outer edge, said holes being equidistantly spaced and adapted to receive the clamping screws, for which there are provided tapped holes 17 in the frame 10.

Formed in the disk 14 is the bevelled hole 18 which is eccentric with relation to the exterior of the disk 14. In the hole 18 is the eccentric flange 19 of a bearing housing 20, within which is mounted a self-aligning bearing 21, which supports the shaft 22 on which, in this instance, is mounted a V-grooved pulley 23 which carries a belt 24. The outer edge 25 of the eccentric flange 19 is bevelled to match the bevelled hole 18 in the disk 14. The tightening of the screws 16 clamps the flange 19 in a fixed position due to the contacting bevelled edges 18 and 25.

Around the interior of the ring 11 are disposed the numbers 26 which extend around 180° of the ring. The ring 14 has an indicating arrow 27 which can register with the numbers 26.

2

The inner edge of the bevelled hole 18 of the disk 14 has numbers 28 formed around its circumference, while the outer edge of the eccentric flange 19 has an indicating arrow 29 formed thereon which can register with the numbers 26.

In Fig. 3 is shown somewhat diagrammatically the operation of the device wherein the straight line 30 represents the travel of the shaft center and the semi-circular line 31 represents the path of travel; that is to say, the radii of eccentricity form the sides of toggle joints or braces between the housing 20 and the frame 10. If, for example, it is desired to move the center of the shaft 22 along the line 30 for the purpose of adjusting the tension on the belt 24, or along the chain or belt carried by the shaft 22, then the first step is to move the disk 14, for example, until the arrow 27 registers with its number 2 and then put the screws 16 into place in the holes 15 without tightening, after which the indicator 29 is moved to its corresponding number 2 along the edge 18 and the screws 16 tightened.

It will be noted that the inner set of numbers 28 extend around the complete circumference of the hole 18, while the outer set of numbers 26 extend only around one-half of the interior of the ring 11; that is, one disk must be moved twice as far as the other in order to maintain the center of the shaft 22 along the line 30. It can thus be seen that by a very simple and inexpensive arrangement a belt may be tightened or loosened any predetermined amount along the line 30, or the shaft axis may be raised or lowered with relation to the line 30 and thereafter maintained at this level by merely maintaining a fixed relationship between the numbers on the disk and their corresponding indicating arrows; that is to say, if a 4 on the inner disk and a 2 on the outer disk would give the desired position for the shaft 22, then any similar combination of numbers separated by 2, such as 7 and 5, 3 and 1, etc., would hold the shaft 22 at the same elevation above or below the line 30.

45 I claim:

A shaft mounting comprised of a side frame, a journal having an eccentric flange formed thereon, a revolvable disk having a circular opening therein eccentric with relation to the circumference of said disk and within which said flange can turn, a journal on said frame for said disk, said disk supported by said frame and having holes formed concentric with and equidistantly around said disk, screws for clamping said perforated disk to said frame, the journal on said

frame having a series of calibrations around one hundred eighty degrees thereof corresponding with the spacing of the holes in said disk, said disk having graduations around the full three hundred sixty degrees of the opening therein 5 with angular spacing two times as great as the angular spacing of the holes in said disk whereby said journal and disk may be revolved in opposite directions and equal number of calibrations and cause the axis of said shaft to move in plane. 10
